UNITED STATES PATENT OFFICE.

EDWIN W. WEBB AND CHARLES S. WALTON, OF CHICAGO, ILLINOIS, ASSIGNORS TO STANDARD CAR TRUCK COMPANY, OF CHICAGO, ILLINOIS, A CORPORATION OF NEW JERSEY.

CAR-TRUCK.

1,241,688.

Specification of Letters Patent.

Patented Oct. 2, 1917.

Application filed September 9, 1916. Serial No. 119,240.

To all whom it may concern:

Be it known that we, EDWIN W. WEBB and CHARLES S. WALTON, citizens of the United States, residing at Chicago, in the county of 5 Cook and State of Illinois, have invented certain new and useful Improvements in Car-Trucks; and we do hereby declare the following to be a full, clear, and exact description of the invention, such as will enable others skilled in the art to which it 10 pertains to make and use the same.

Our invention relates to improvements in car trucks, and particularly to six wheeled equalizing car trucks of the type disclosed 15 and broadly claimed in our co-pending application, entitled "Car trucks," filed August 12, 1916, under S. N. 114,556.

To the above end, generally stated, the invention consists of the novel devices and 20 combinations of devices hereinafter described and defined in the claims.

In the accompanying drawings, which illustrate the invention, like characters indicate like parts throughout the several views.

25 Referring to the drawings,

Figure 1 is a view, principally in side elevation, of the improved car truck with some parts shown in vertical section and some parts diagrammatically illustrated by means 30 of broken lines;

Fig. 2 is a fragmentary vertical section taken on the line 2—2— of Fig. 1;

Fig. 3 is a fragmentary vertical section taken on the line 3—3— of Fig. 1, with some 35 parts removed; and

Fig. 4 is a fragmentary plan view of the improved car truck.

Each side frame of the improved car truck is indicated by the numeral 1 and, as 40 shown, is of cast steel with a general cross section in the form of a box, the walls of which are suitably reinforced. The upper sections of two-part depending pedestals 2 are cast integral with the side frames 1 and 45 the lower sections thereof are detachably, but rigidly secured to said upper sections by nut-equipped bolts 3. The lower extremities of each pair of pedestals 2 are rigidly connected by a tie bar 4. These tie bars 4 are detachably secured to the pedestals 2 by 50 nut-equipped bolts 5 and the ends thereof are bent upward and engage the outer faces of the pedestals to prevent lateral separation thereof. Chafing plates 6 extend substan-

tially full length of the pedestals 2 and cover 55 the joints between the sections thereof.

A pair of bolster openings 7 is formed in the side frame 1, one on each side of the intermediate pair of pedestals 2, and a spring seat 8 is formed in the side frame 1, directly 60 below each bolster opening 7. The walls of the side frame 1, between each pair of pedestals 2, are extended downward to afford relatively deep pairs of flanges 9 at the ends of the spring seats 8. Horizontally spaced 65 pairs of spacing thimbles and bolts 10 connect each pair of flanges 9 at their lower extremities. In each end of the side frame 1, is a transverse segmental seat 11 formed in the top member of the side frame for a rock- 70 ing abutment. Over each pair of pedestals 2, is formed in the side frame 1 a horizontally elongated opening 12, the purpose of which will presently appear.

The car truck wheels and their axles are 75 indicated by the numeral 13 and the journal boxes therefor are indicated as entireties by the numeral 14, with the exception of rectangular bearing seats 15 formed in the tops thereof. The journal boxes 14 may be 80 of any desired form, are mounted between the pedestals 2, and have on their sides the customary pedestal guides.

The side frames 1 are rigidly connected by two pairs of angle tie bars 16 having 85 their horizontal flanges turned toward each other and the ends thereof rest on brackets 17 to which they are riveted. These brackets 17 are cast integral with the inner flanges 9 and project inward therefrom. 90 The vertical flanges of each pair of tie bars 16 are turned upward and their horizontal flanges are edgewise spaced apart to permit the escape of dust and dirt therebetween.

The bolster of the improved car truck 95 is of the double type and, as shown, is made up of a center beam 18, outer beams 19 and tie I-beam 20. The bolster beams 19 are located directly over each pair of tie bars 16, extend between the vertical flanges 100 thereof and have their ends inserted through the bolster opening 7. Roller contours 21 are formed on the under faces of the bolster beams 19 and rest on lateral motion rollers 22. These rollers 22, in turn, are mounted 105 in roller contours 23 formed in roller bases 24, seated on the bottoms of the bolster openings 7. On the sides of the bolster

beams 19, are stop lugs 25 arranged to engage the inner faces of the side frames 1 to limit the lateral movement of the bolster. The beams 19 are rigidly connected and held 5 in parallel arrangement by the tie bars 20, the ends of which rest upon said beams 19 and are bolted thereto. The center beam 18 is supported by the tie beams 20 and its ends rest on the horizontal flanges of said tie beams and are riveted to the webs thereof. A lower center bearing 26 is cast integral with the center beam 18.

While the bolster shown is made up of several members rigidly connected by bolts 15 and rivets, it is, of course, understood that the same may be cast as an entirety. Side bearing plates 27 are riveted to the tie beams 20 in line with the center beam 18 and prevent excessive rocking of the car.

20 Intermediately fulcrumed on each journal box 14, is an equalizing lever 28 having on its under side a fulcrum lug 29 mounted in the bearing seat 15 of the respective journal box 14. These equalizing levers 28 extend 25 transversely of the journal boxes 14, are located within the side frames 1 and have in each of their ends an elongated vertically extended aperture 30. Rocking abutments 31 are mounted in the seat 11 and are provided with pairs of oppositely extended fulcrum lugs 32 mounted in notches 33 formed in the outer ends of the outer equalizing 30 levers 28. Depending lugs 34 on the abutments 31 extend into the underlying apertures 30 in the outer ends of the outer equalizing levers 28 and hold said abutments in position.

The side frames 1 are supported on heavy semi-elliptical springs 35 which, in turn, are 40 supported by links 36 from the inner ends of the outer equalizing levers 28 and the intermediate equalizing levers 28. The links 36 are flat and are extended through the apertures 30 in the inner ends of the outer

45 equalizing levers 28 and the intermediate equalizing levers 28. Fulcrum lugs 37, in the form of keys, are extended transversely through the links 36 at the ends thereof. The upper fulcrum lugs 37 are seated in 50 notches 38, formed in the upper surfaces of the equalizing levers 28, and support the links 36 therefrom. The lower fulcrum lugs 37 are seated in notches 39 formed in the under sides of the thickened ends of the 55 lowermost leaves of the springs 35 and support said springs thereon. The links 36 are loosely extended through the apertures 30 to permit the required flexibility of the levers 28, abutments 31, springs 35, and links 60 36. The intermediate portions of the springs 35 are mounted in the seats 8 between the flanges 9 and are located above the thimbles and bolts 10. Obviously, these thimbles and bolts 10 rigidly connect the flanges 9 and 65 reinforce the same. The flanges 9 hold the

springs 35 against lateral and horizontal angular movements in the seats 8 and the ends of their lower leaves are bifurcated to receive the links 36.

Brake hangers 40 are riveted to the inner 70 sides of the side frames 1. By reference to Fig. 3, it will be noted that the upper members of the pedestals 2 and the upper ends of the chafing plates 6 are notched to afford clearance for the equalizing levers 28. In 75 assembling the improved car truck, the openings 12 in the side frames 1 make it extremely simple and easy to position the equalizing levers 28 on the journal boxes 14, connect the links 36 to the equalizing levers 80 28 and also to position the abutments 31.

It will be noted that the pedestals 2, equalizing levers 28, springs 35, links 36, are all of one pattern, respectively, making the construction simple and easy to replace parts, 85 in case of wear or breakage.

From the above description, it is evident that the load of the car is directly on the double bolster and it, in turn, bears directly 90 on the side frames through the lateral motion rollers. The weight on the side frames is applied directly over the several springs 35, which carry said side frames from the journal boxes through the equalizing levers and links. By the construction and arrangement of parts just referred to, each wheel 95 is allowed to move vertically, independent of the others thereof.

The compactness of the above described invention is such that an extra pair of 100 wheels is added, without increasing the length of the truck over a four wheeled truck, thereby increasing the capacity of the truck with no additional weight placed on a given length of roadbed.

105 What we claim is:—

1. In a car truck, the combination with side frames, a bolster, anti-friction bearing devices supporting the bolster from the side frames and journal boxes, of equalizers, and leaf springs carried by the equalizers and supporting the side frames under the bolster.

110 2. In a car truck, the combination with side frames and journal boxes, of equalizing levers intermediately fulcrumed on the journal boxes, abutments between the outer ends of the equalizing levers and side frames, leaf springs carried by the inner ends of the equalizing levers and supporting the side frames, and anti-friction bearing devices on the side frames over the springs.

115 3. In a car truck, the combination with side frames and journal boxes, of equalizing levers intermediately fulcrumed on the journal boxes, abutments between the outer ends of the equalizing levers and side frames, leaf springs carried by the inner ends of the equalizing levers and supporting the side frames, lateral motion bearing devices on 120 125 130

the side frames over the springs, and a bolster carried by the lateral motion bearing devices.

4. In a car truck, the combination with 5 side frames, a bolster and journal boxes, of equalizing levers intermediately fulcrumed on the journal boxes, rocking abutments between the outer ends of the equalizing levers and side frames, and springs carried by 10 inner ends of the equalizing levers and supporting the side frames under the bolster.

5. In a car truck, the combination with 15 side frames having bolster openings and pairs of laterally spaced flanges therebelow, a bolster having its ends extending into the bolster openings and spring seats under the bolster and between said flanges, of equalizing levers intermediately fulcrumed on the journal boxes, abutments between the outer 20 ends of the equalizing levers and side frames, and leaf springs mounted in said seats and having their ends supported from the equalizing levers.

6. In a car truck, the combination with 25 side frames having bolster openings and pairs of laterally spaced flanges therebelow, a bolster having its ends extending into the bolster openings and spring seats under the bolster and between said flanges, of equalizing 30 levers intermediately fulcrumed on the journal boxes, abutments between the outer ends of the equalizing levers and side frames, leaf springs mounted in said seats and having their ends supported from the 35 equalizing levers, and spacing devices connecting the pairs of flanges below the springs.

7. In a car truck, the combination with 40 side frames and journal boxes, said side frames having bolster openings and depending flanges, spring seats between said flanges, of equalizing levers intermediately fulcrumed on the journal boxes, abutments between the outer ends of the equalizing le-

vers and side frames, and leaf springs 45 mounted in said seats and having their ends supported from the equalizing levers.

8. In a car truck, the combination with 50 side frames and journal boxes, said side frames having bolster openings and depending flanges, spring seats between said flanges, of equalizing levers intermediately fulcrumed on the journal boxes, abutments between the outer ends of the equalizing levers and side frames, leaf springs mounted 55 in said seats and having their ends supported from the equalizing levers, and lateral motion bearing devices in the bolster openings.

9. In a six wheeled car truck, the combination with side frames, journal boxes and a double bolster, of equalizing levers intermediately fulcrumed on the journal boxes, abutments between the outer ends of the outer equalizing levers and side frames, and 60 leaf springs supported from the inner ends of the outer equalizing levers and the intermediate equalizing levers and supporting the side frames directly under the double 65 bolster. 70

10. In a six wheeled car truck, the combination with journal boxes and a double bolster, of equalizing levers intermediately fulcrumed on the journal boxes, rocking abutments between the outer ends of the outer 75 equalizing levers and side frames, and leaf springs supported from the inner ends of the outer equalizing levers and the intermediate equalizing levers and supporting the side frames directly under the double 80 bolster. 80

In testimony whereof we affix our signatures in presence of two witnesses.
